UNITED STATES PATENT OFFICE.

FRED B. COREY, OF SCHENECTADY, NEW YORK, ASSIGNOR TO GENERAL ELECTRIC COMPANY,
A CORPORATION OF NEW YORK.

RAILWAY-SIGNAL.

No. 876,944.

Specification of Letters Patent.

Patented Jan. 21, 1908.

Application filed October 6, 1905. Serial No. 281,669.

To all whom it may concern:

Be it known that I, FRED B. COREY, a citizen of the United States, residing at Schenectady, county of Schenectady, State of New York, have invented certain new and useful Improvements in Railway-Signals, of which the following is a specification.

My invention relates to railway signals of the semaphore type, and its object is to provide novel and efficient means for giving night indications.

It has been found in practice that when the colored roundels are placed in the semaphore casting exposed to the weather they frequently become covered with snow and sleet, so that they are no longer translucent. This is clearly a source of danger, as a signal may be passed at night without being seen by the engineer. Certain signals have been arranged heretofore with the roundels and lamp all inclosed in a casing so as to be protected from the weather. With this arrangement it is necessary to provide some sort of connection between the semaphore signal and the roundels so that they will be moved in accordance with the movements of the semaphore arm.

The object of my invention is to provide a simple arrangement for controlling the roundels which may readily be applied to standard signals, and in its broadest aspect my invention consists in the combination with a semaphore signal, of a casing comprising a lens, a lamp inclosed in the casing, one or more translucent disks movable between the lamp and the lens, and electromagnetic controlling means for the disk controlled by switch contacts operatively related to the semaphore arm.

My invention further consists in so arranging the disks or roundels and their operating mechanism that when the operating means is deenergized or disabled the roundels will move to such a position that a danger signal will be given.

My invention will best be understood by reference to the accompanying drawings, in which

Figure 1 shows a side elevation of a signal arranged in accordance with my invention with a portion of the casing inclosing the operating mechanism partly broken away; Fig. 2 shows a front view of the same with the casing similarly broken away; and Fig. 3 shows a diagram of circuit connections.

In the drawings A represents a signal-post on which is mounted a casing B.

C represents the drive-shaft for the semaphore arm which is suitably journaled within the casing and driven by suitable operating mechanism. The operating mechanism for the semaphore arm is not shown, but may be of any well-known type, such, for instance as that shown in Patent No. 778,037, Herman.

D represents the semaphore arm which is mounted on the drive-shaft C outside the casing, and is provided with a counter-weight d, which is adapted to drive it to danger position when released by the operating mechanism.

R, Y and G represent three electromagnets, the circuits of which are controlled by the contacts e on the end of the signal drive-shaft C, which engage suitable stationary contacts e in circuit with the electromagnet. The cores of the electromagnets are connected through pivoted bell-crank levers h¹, h² and h³ to the pivoted translucent disks or roundels r, y and g. These roundels are of different colors as, for instance, red, yellow and green, as indicated by the letters applied to them, so as to give three distinct color indications of caution, clear and danger, corresponding to positions of the semaphore arm, and are pivoted to move between the lamp L and the lens l which is inserted in the wall of the casing B. As the different disks move in front of the lamp different colored indications are given. Since the roundels are inclosed within the casing they are protected from being obscured by snow and sleet. The outer surface of the lens l is the only exposed surface which must transmit light, and since the lamp L heats the casing, snow or sleet striking on the lens l will be melted and will run off. The signal is consequently much more reliable than would be the case if the roundels were mounted on a spectacle casting outside the casing exposed to the weather in the usual manner.

In order that a danger indication may be given at night, if the source of current for the electromagnets fails, or the circuits are broken, or the magnets are in any way disabled, I so arrange the disks that when they are released by the electromagnets they move by gravity to predetermined positions in which the red roundel is in line with the lamp, while the other two disks are out of

line with the lamp. One arrangement for accomplishing this result is that shown in the drawings, in which the red disk is so arranged that its range of movement is from a position 5 in front of the lamp upwards, while the other two disks have a range of movement from a position in front of the lamp downwards, and all the disks are arranged to return to their lowest position automatically by gravity 10 when released.

The circuit connections may be arranged as shown in Fig. 3, which shows three signals D^1 , D^2 and D^3 , in danger, caution and clear positions respectively. With the signal D^1 15 at danger position, as shown, the contact c^1 on the signal-shaft is out of engagement with the stationary contacts e^1 , so that the circuits of all the electromagnets are broken and the roundels are allowed to drop to their lowest 20 positions. The lowest position of the roundel r is in line with the lamp L^1 and lens l^1 , while the other two roundels g and y are out of line with the lamp so that a red or danger indication is given. When the signal 25 arm is in caution position, as indicated at D^2 , a circuit is closed from the source of current f^2 through both magnets R and Y . The roundels r and y are consequently raised to their highest positions. This brings the red 30 disk out of line with the lamp and the yellow disk y in line with the lamp, so that the yellow or caution indication is given. With the signal in clear position, as shown at D^3 , the 35 magnets R and G are energized so that the green disk g is in line with the lamp, and a green or clear indication is given.

By inclosing the lamp roundels and operating magnets in a separate casing by themselves my invention may be applied directly 40 to any existing type of signal without necessitating any other modification of the signal than placing the necessary controlling contacts for the roundel magnets on the signal drive-shaft, or on any other suitable part of 45 the operating mechanism.

I do not desire to limit myself to the particular construction and arrangement of parts here shown, but aim in the appended claims to cover all modifications which are 50 within the scope of my invention.

What I claim as new and desire to secure by Letters Patent of the United States, is, —

1. A semaphore signal comprising a casing having a lens, a lamp inclosed in said casing 55 a translucent disk movable between said lamp and said lens, an electromagnet within said casing controlling said disk, a semaphore-arm movable outside but adjacent to said casing, and switch contacts controlling said 60 electromagnet and controlled by the semaphore signal.

2. In combination with a semaphore signal and its operating mechanism, a casing comprising a lens, a lamp inclosed in said casing,

a plurality of translucent disks of different colors movable between said lamp and said lens to give different signal indications, a plurality of electromagnets controlling said disks, and switch contacts controlling said electromagnets and controlled by said semaphore signal.

3. In a combination, a semaphore signal adapted to give three different indications, operating mechanism therefor, a casing comprising a lens, a lamp inclosed in said casing, 75 three translucent disks of different colors movable between said lamp and said lens, a plurality of electromagnets controlling said disks, and switch contacts controlling said electromagnets and controlled by said semaphore signal.

4. In combination with a semaphore signal and its operating mechanism, a casing comprising a lens, a lamp inclosed in said casing, 85 a plurality of translucent disks of different colors movable between said lamp and said lens to give different indication, electromagnets within said casing, operative connections between said magnets and said disks so arranged that when said magnets are deener- 90 gized the disk for the "danger" indication automatically assumes a position in line with said lamp and said lens and the other disk or disks automatically assume a position out of 95 said line, and switch contacts controlling 95 said magnets and controlled by said semaphore signal.

5. In a railway signal, a lamp, a plurality of disks of different colors independently movable in front of said lamp to give different indications, said disks being arranged to move automatically by gravity when released by the operating means to positions in which the disk for the "danger" signal is in front of said lamp and the other disk or disks are out of line with said lamp, and electromagnetic operating means for moving said disks out of said positions.

6. In a railway signal, a lamp, a plurality of pivoted disks of different colors independently movable in front of said lamp to give different indications, the range of movement of the disk for the "danger" indication extending upwards from a position in front of said lamp and the range of movement of the other disk or disks extending downwards from a position in front of said lamp and all of said disks being automatically movable by gravity to their lowest positions, and electromagnetic operating means for raising said disks from said lowest positions.

In witness whereof, I have hereunto set my hand this fourth day of October, 1905.

FRED B. COREY.
